UNITED STATES PATENT OFFICE

GEORGE F. EBERHARD, OF CLEVELAND, OHIO.

DESIGN FOR A BUCKLE.

SPECIFICATION forming part of Design No. 18,067, dated February 21, 1888.

Application filed December 27, 1887. Serial No. 259,190. Term of patent 3½ years.

To all whom it may concern:

Be it known that I, GEORGE F. EBERHARD, of Cleveland, in the county of Cuyahoga and State of Ohio, have invented and produced a certain new and useful Design for Buckles; and I do hereby declare the following to be a full, clear, and exact description of the same, reference being had to the accompanying drawings, forming a part thereof.

10 Figures 1 and 2 are plans. Figs. 3 and 4 are side elevations.

My new design relates to the variety of buckle having a cross-bar midway thereof for attaching the buckle-tongue.

15 The essential features of my new design are as follows: First, the sides *a* of the buckle are thin and of suitable depth for joining the cross-bar, so as to present in plan only the thin edges of these side pieces, such buckle being only a

20 trifle wider at any part than the strap that the buckle is intended to receive; second, as shown

in Figs. 3 and 4, the top edges of the side members, *a*, of the buckle are substantially straight or so nearly straight as to conceal the edges of the strap.

Buckles of this design present a very neat and tasty appearance whether viewed in plan or side elevation.

What I claim is—

The design for buckle herein shown and described, consisting in plan of broad ends and thin parallel sides and in elevation of deep sides straight and unbroken along the upper edges thereof between the end members of the buckle, substantially as set forth.

In testimony whereof I have signed this specification, in the presence of two witnesses, this 27th day of October, 1887.

GEORGE F. EBERHARD.
